(57) **CLAIM**

The ornamental design for an electric bicycle, as shown and described.

DESCRIPTION

FIG. 1 is a top, front, and left side perspective view of an electric bicycle embodying my new design;

FIG. 2 is a bottom, rear and right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a partial and enlarged perspective view of area 9 in FIG. 1;

FIG. 10 is a partial and enlarged perspective view of area 10 in FIG. 2; and,

FIG. 11 is a partial and enlarged perspective view of area 11 in FIG. 7.

The broken lines depict portions of the electric bicycle that form no part of the claimed design.

1 Claim, 11 Drawing Sheets
